(57) **CLAIM**

The ornamental design for an electric shaver, as shown and described.

DESCRIPTION

FIG. 1 is a perspective view of our new design for an electric shaver;

FIG. 2 is a front elevation view of our new design;

FIG. 3 is a rear elevation view thereof;

FIG. 4 is a top plan view of thereof;

FIG. 5 is a bottom plan view thereof;

FIG. 6 is a left side elevation view thereof; and,

FIG. 7 is a perspective rear view of our new design with a rear blade projected as a trimmer.

The right side elevation view is a mirror image of the left side elevation view shown in FIG. 6.

The structures shown in broken lines are for illustrative purposes only and form no part of the claimed design.
